UNITED STATES PATENT OFFICE.

JOHN MOHN, OF DETROIT, MICHIGAN.

DESIGN FOR A TAP-CASING.

SPECIFICATION forming part of Design No. 24,859, dated November 5, 1895.

Application filed January 22, 1895. Serial No. 535,826. Term of patent 7 years.

To all whom it may concern:

Be it known that I, JOHN MOHN, a citizen of the United States, residing at Detroit, in the county of Wayne and State of Michigan, have invented and produced a new and original Design for Coupling-Casings, of which the following is a specification, reference being had therein to the accompanying drawings.

The invention relates to an original design for a tap-coupling casing, and is shown in the accompanying drawings, wherein—

Figure 1 is an elevation, and Fig. 2 is a bottom view.

A designates a cylindrical body; B, a circular base of a diameter greater than the body. The base has rounded edges C. On the top of the body is the circular band E, resting on an extension D of the body, which

extension is circular and of larger diameter than the body, its lower edge being rounded, ²⁰ as shown. Springing from opposite sides of the part E are the lobe-shaped projections F.

G designates a cylindrical branch at the top of the body portion, having a flanged edge H.

The essential feature of the design is the ²⁵ casing, as shown.

What I claim is—

The design for a tap casing, substantially as shown and described.

In testimony whereof I affix my signature ³⁰ in presence of two witnesses.

JOHN MOHN.
